DESIGN FOR EMBROIDERED NET

Anton Walter, New York, N. Y.

Application October 17, 1936, Serial No. 65,331

Term of patent 3½ years

To all whom it may concern:

Be it known that I, Anton Walter, a citizen of the United States of America, residing in Manhattan, county of New York and State of New York, have invented a new, original, and ornamental Design for Embroidered Net, of which the following is a specification, reference being had to the accompanying drawing, forming part thereof, wherein,

The figure is a plan view of a piece of embroidered net showing my new design.

The design is characterized by groups of two daisy-like flowers arranged on a netted background as shown. It comprises petals defined by tinsel threads, the centers of which being of tufted chenille of contrasting color.

I claim:

The ornamental design for embroidered net, substantially as shown and described.

ANTON WALTER.
